The Schedule referred to in these Letters Patent and making part of the same containing a description in the words of the said Elisha Perkins himself of his improvement in the mode of spreading or manufacturing blister-plaster:

No all to whom this Schedule shall come

Elisha Perkins of the City of Baltimore in the state of Maryland Physician and Surgeon greeting. Be it known that I, said Elisha Perkins have invented made and applied to use a new & useful improvement in the mode of spreading or manufacturing blister-plaster (commonly called blister-cloth) which I call my "Improved Blister-plaster" & which I specify in the words following, viz: This improvement consists in the spreading of the plaster by means of two cylindrical rollers of cast iron, brass or other hard metal. In spreading the fly, altogether upon the surface of the plaster, whereby its action when applied to use, is rendered uniform, certain & effectual, instead of mixing the fly, as has been heretofore done, throughout the whole of the composition matter of the plaster, which causes the action of the fly, to be always in some degree uncertain, sometimes only partially often wholly vanishing. I use rollers about twenty-five inches in length, & about five inches in diameter, they may be a little smaller or larger with equal advantage. They are fixed in a frame so that the rollers lie in a horizontal position, one directly above the other, in the manner of those used in making copper plates, or in rolling copper & iron sheets. The motion is communicated to the lower cylinder by a crank or wheel affixed to one end, which I turn by hand, but which may be turned by any other power, motion is communicated from the under roller to the upper one by small spur-wheels attached to the axis or gudgeons of the rollers at the end where the crank is so that the velocity of both rollers is the same, when in motion. When to be used in spreading the plaster, the upper roller is taken out of the frame, & heated in boiling water, sufficiently to soften the composition matter of the plaster to be spread. Thus heated the cylinder or roller is fixed in the frame, both being properly screwed up & adjusted, one end of the cloth is put smooth between the rollers on the side to be received while they are in motion, & at the same

time a roll of the composition matter for the plaster without any admixture of the fly, is laid upon & across the cloth, & kept perfectly & firmly against it by the rollers until the whole length of the cloth, which may be two yards more or less, has passed thro' the rollers, the rollers, being drawn by hand on the side opposite to that in which it enters so as to prevent it from being wrapped around the lower cylinder & to keep it smooth. In being thus passed thro' the rollers, the plaster is uniformly, firmly, & completely spread. It is then delivered to the hands of another person, who immediately spreads the fly over the surface, while the plaster is snarled & carefully folded up the cloth & prepared together with the hands to cause the fly to adhere, when the rollers are cold, the plaster being also cold, or cool, is, with the fly dusted thereon as above mentioned, again passed thro' the rollers which effectually secure the fly upon the surface, & prepares the plaster for use. The smaller of convenience I put up cloths, used two yards long, in ten bags for safe keeping, for easy transportation. This however I do not consider a necessary part of my specification.

The testimony that the above is a true specification of my said improvement as above described, I have here set my hand & seal the twenty sixth day of Decr^r in the year of our Lord one thousand eight hundred and twenty nine.
